CRUCIBLE SUPPORT

Raymond D. York, University, Va., assignor to
Raymond D. York, as trustee

Application December 16, 1938, Serial No. 246,235

9 Claims. (Cl. 22—8)

This invention relates to a crucible support and more particularly to a support which will facilitate the handling of a crucible in carrying it to and from the furnace.

5 The principal object of this invention is to provide a mechanism which is particularly convenient and efficient for use in engaging and supporting a crucible during that time in which the crucible is being carried to and from a furnace.

10 A further object is to provide a device which, in addition to providing a simple and efficient means for manually removing a crucible from a furnace, will also readily permit the pouring of the molten metal from the crucible after its removal from the furnace.

15 A further object is to provide a supporting structure carrying novel article gripping members which are relatively movable toward and away from each other, whereby an article positioned between said gripping members may be clamped therebetween and supported thereby.

20 A further object is to provide a supporting structure carrying a pair of article gripping members, one of which is rigidly secured to the supporting structure and the other of which is movable with respect thereto into engagement with an article positioned between the gripping members, whereby the article will be clamped between and supported by both of the gripping members.

25 A further object is to provide a supporting structure having a pair of gripping members carried thereby, together with resilient means for preventing relative movement of said members away from each other to maintain them in clamped engagement with an article.

30 A further object is to provide a supporting structure carrying a pair of gripping members respectively fixed and movable with respect thereto, and to provide resilient means for moving the movable member toward and maintaining it in clamped engagement with an article arranged between said gripping members.

35 Other objects and advantages of the invention will become apparent during the course of the following description.

In the drawing I have shown one embodiment of the invention. In this showing:

40 Figure 1 is a side elevation showing the mechanism in operative engagement with a crucible located in a furnace,

45 Figure 2 is a plan view of the mechanism shown in Figure 1,

50 Figure 3 is a sectional view taken on line 3—3 of Figure 1,

55 Figure 4 is a sectional view taken on line 4—4 of Figure 1, and

Figure 5 is a perspective view of a part of the mechanism.

Referring to Figure 1, the numeral 10 indicates a furnace having a crucible 11 supported therein on a pedestal 12. The numeral 13 indicates the mechanism as a whole by which the crucible 11 may be manually transported, the mechanism 13 being shown in operative position 10 for the removal of the crucible 11 from the furnace.

The mechanism 13 comprises a supporting structure 14 having spaced parallel bars 15 and 16, rigidly fastened to transverse plates 17 and 18 located at opposite ends thereof. The plates 17 and 18 depend a substantial distance below the bars 15 and 16 and each is provided with a pair of handles 19 secured adjacent the lower edge thereof. 20

Gripping members 20 and 21 are provided and have gripping surfaces which are engageable with the surface of the crucible 11 for supporting the same. A pair of brackets 22 and 23 are respectively secured to the bars 15 and 16 and cooperate therewith to support the gripping member 20. Likewise, a pair of brackets 24 and 25 are respectively secured to the members 15 and 16 respectively and these brackets support the gripping member 21. 30

The gripping member 20 is rigidly secured to the supporting structure 14 by two fastening members 26 and 27 as best shown in Figure 3. The gripping member 21 is pivotally supported with respect to the supporting structure 14 by a pivot pin 28 extending through the lower ends of the brackets 24 and 25 as shown in Figure 4. A resilient bar 29 is secured at one end to the upper end 30 of the member 21 and is used as a lever arm for forcibly moving the member 21 about its pivot 28 toward the gripping member 20 to securely clamp the gripping members against a crucible arranged therebetween. 35

Plates 31 and 32 are secured to and project upwardly above the bars 15 and 16 respectively and 40 are located in such a position that the bar 29 will occupy a position between the plates 31 and 32 when the gripping members 20 and 21 are in engagement with a crucible. The plate 32 has a plurality of openings 33 formed therein which 45 are respectively in alignment with similar openings 34 formed in the plate 31. With the gripping members 20 and 21 in clamping engagement with the crucible 11 and the member 29 positioned between the plates 31 and 32, a pin 35 50

55

may be passed through aligned openings 33 and 34 in the plates 32 and 31, respectively, above the bar 29 to lock the latter in operative position. The bar 29, being resilient, will be sprung 5 downward by the application of force after initial engagement of the gripping member 21 with the crucible 11 and it will be obvious that the resilience of the member 29, tending to restore it to the position shown in dotted lines in Figure 1, will be prevented from swinging upwardly by the locking pin 35 thereby holding the member 21 in tight engagement with the crucible 11.

The gripping surfaces of the members 20 and 21 are shaped to conform to the crucible to be 15 engaged and supported thereby and different sizes may be provided for different sized crucibles. In order that the gripping surfaces of the members 20 and 21 will be properly positioned with respect to the sides of the crucible, it is de- 20 sirable to provide adjustable means for positioning the gripping members 20 and 21 with respect to the crucible. This is accomplished by an adjustable plate member 36 which is engageable with the top of the crucible 11. The plate 36 is 25 provided with upright members 38 and 39 carried thereby which are slidable in guides 40 and 41 secured by suitable fastening devices to the bars 15 and 16. Set screws 42 and 43 are provided for adjustably positioning the members 38 30 and 39 in the guides 40 and 41 in order that the plate 36 will be properly positioned with respect to the gripping members 20 and 21. A similar arrangement for positioning the gripping members with respect to the top of the crucible is 35 shown in my copending application filed September 27, 1938, Serial No. 232,005.

The operation of the apparatus is as follows:

The members 38 and 39 are adjusted to place the plate 36 at a proper position relative to the 40 gripping members 20 and 21 in order that the gripping members will be placed at a proper position with respect to the side of the crucible to engage thereagainst. The mechanism 13 is then lowered until the plate 36 contacts the upper edge 45 of the crucible 11. The mechanism 13 is placed in a position with the immovable gripping member 20 in engagement with one side of the crucible 11, whereupon the movable gripping member 21 is moved about its pivot 28 toward and into en- 50 gagement with the other side of the crucible. A downward pressure is applied to the free end of the resilient member 29 to force the gripping member 21 into tight engagement with the side of the crucible. Such downward pressure will cause a 55 deformation of the resilient member 29 from the dotted line position to the solid line position in Figure 1. The locking pin 35 is then inserted through a pair of aligned openings 33 and 34, in the members 32 and 31 respectively, immediately 60 above the resilient member or lever 29. The locking pin 35 will retain the member 29 in its deformed position and the crucible 11 will thereby be securely clamped between the crucible gripping members 20 and 21.

65 The crucible 11 may then be removed from the furnace by operators who will grasp the handles 19 and lift the mechanism 13 and thereby remove the crucible 11 from the furnace.

A decided advantage is secured by having the 70 handles 19 located as shown in Figure 1. By having the handles located in a common plane substantially lower than the supporting frame 14, such plane may be located just above the center of gravity of the combined mechanism 13 and 75 crucible 11. This arrangement will enable the

operators to tilt the crucible supported by the mechanism 13 to pour molten metal therefrom with a minimum of effort. In order to tilt the crucible to pour metal therefrom, it will only be necessary for the operators to apply slightly more 5 force to the handles located at one side of the parallel members 15 and 16 than is applied to the handles 19 located at the other side thereof.

When it is desired to release the crucible from the mechanism, it merely is necessary for an operator to exert a downward force on the free end of the bar 29 to relieve the pressure thereof from the pin 35. This pin then may be easily withdrawn, whereupon the bar 29 is free to move upwardly to release the gripping member 21 from 15 the crucible. Thus the mechanism will be free to be moved upwardly wholly out of engagement with the crucible.

From the foregoing, it will be apparent that I 20 have provided a simple and inexpensive apparatus for removing a crucible containing molten metal from a furnace. In addition to providing mechanism which greatly simplifies the removal of a crucible from a furnace, I have also provided mechanism which will enable the metal to be 25 poured from the crucible with a minimum of effort.

It is to be understood that the form of the invention herewith shown and described is to be 30 taken as a preferred example of the same and that various changes in the shape, size and arrangement of parts may be resorted to without departing from the spirit of the invention or the scope of the subjoined claims.

I claim:

1. In mechanism for engaging and supporting a crucible, a supporting structure, a rigid stationary crucible gripping device fixed thereto, a rigid movable crucible gripping device carried by said supporting structure, means including a resilient member formed as a handle engageable by the hand of the operator for moving said movable gripping device toward said stationary gripping device to resiliently clamp a crucible therebetween, and locking means arranged to form a direct positive connection between said last named means and said supporting structure for holding said movable gripping device in crucible-engaging position, said resilient member being arranged between said locking means and said movable gripping device.

2. In mechanism for engaging and supporting a crucible, a supporting structure, a rigid stationary crucible gripping device fixed thereto, a rigid movable crucible gripping device, pivoted to said supporting structure, means including a resilient member for moving said movable gripping device toward said stationary gripping device to resiliently clamp a crucible therebetween, and means connected to said supporting structure and directly 60 engaging said resilient member to hold the latter under tension and clamp said movable gripping device against the article.

3. In mechanism for engaging and supporting a crucible, a supporting frame, a rigid crucible 65 gripping device rigidly secured to said frame, a second rigid crucible gripping device pivoted to said frame, a resilient member connected to said second gripping device for moving it into engagement with an article arranged between said gripping devices, and means carried by said supporting frame and transversely movable with respect thereto to engage said resilient member for preventing movement of said second gripping device out of engagement with said crucible.

4. In mechanism for engaging and supporting a crucible, a rigid supporting structure, a rigid gripping device carried thereby, a second rigid gripping device pivoted on a fixed axis to said supporting structure, and an operating handle for said second named gripping device comprising a resilient bar connected to said second named gripping device and extending a substantial distance therefrom to provide a free end engageable by the hand of the operator.

5. In mechanism for engaging and supporting a crucible, a rigid supporting structure, a rigid gripping device carried thereby, a second rigid gripping device pivoted on a fixed axis to said supporting structure, an operating handle for said second named gripping device comprising a resilient bar arranged adjacent said supporting structure, and means carried by said supporting structure and engageable with said bar to maintain it under tension for resiliently holding said gripping devices in resilient clamping engagement with a crucible therebetween.

6. In mechanism for engaging and supporting a crucible, a rigid supporting structure, a rigid gripping device carried thereby, a second rigid gripping device pivoted to said supporting structure, an operating handle for said second named gripping device comprising a resilient bar arranged adjacent said supporting structure, stationary means carried by said support adjacent said bar, and detachable means carried by said stationary means and engageable with said bar to hold it under tension and maintain said gripping devices in resilient clamping engagement with a crucible therebetween.

7. In mechanism for engaging and supporting a crucible, a rigid horizontal elongated support, a pair of respectively rigid gripping devices depending therefrom, one of said gripping devices being

fixed to said support and the other being pivoted on a fixed axis thereto, and a resilient bar connected at one end to said second named gripping device above said support and forming an operating handle therefor.

8. In mechanism for engaging and supporting a crucible, a rigid horizontal elongated support, a pair of respectively rigid gripping devices depending therefrom, one of said gripping devices being fixed to said support and the other being pivoted on a fixed axis thereto, a resilient bar connected at one end to said second named gripping device above said support and forming an operating handle therefor, and means carried by said support thereabove and engageable with said bar adjacent the free end thereof for holding it under tension and maintaining said gripping devices in resilient clamping engagement with a crucible therebetween.

9. In mechanism for engaging and supporting a crucible, a supporting structure comprising a pair of horizontal rails, a pair of jaw members depending from said rails and having their upper end portions arranged therebetween, means for rigidly securing one of said jaw members to said rails, means for pivoting the other jaw member to said rails for swinging movement on a horizontal axis, an operating handle for said pivoted jaw comprising a resilient bar secured at one end to the upper end of said pivoted jaw and extending a substantial distance toward the adjacent end of said supporting frame, and means carried by said frame and comprising a transverse pin adapted to be fixed in vertically adjusted positions above said frame in engagement with the top of said bar to prevent upward movement of the latter.

RAYMOND D. YORK.
